UNITED STATES PATENT OFFICE.

PAUL WEBSTER TRIER, OF CHICAGO, ILLINOIS.

DESIGN FOR A FOOD HEATER.

Application filed August 3, 1928. Serial No. 27,696. Term of patent 14 years.

To all whom it may concern:

Be it known that I, PAUL WEBSTER TRIER, a citizen of the United States, residing at Chicago, in the county of Cook and State of Illinois, have invented a new, original, and ornamental Design for Food Heaters, of which the following is a specification, reference being had to the accompanying drawing, forming part thereof.

The single figure is a perspective view of a heater showing my new design.

I claim:

The ornamental design for a food heater as shown.

In witness whereof, I hereunto subscribe my name this 26 day of July, 1928.

PAUL WEBSTER TRIER.
